UNITED STATES PATENT OFFICE.

ELIHU THOMSON, OF SWAMPSCOTT, MASSACHUSETTS, ASSIGNOR TO THE
GENERAL ELECTRIC COMPANY, OF NEW YORK.

DESIGN FOR A WING FOR AIR-BLASTS.

SPECIFICATION forming part of Design No. 27,693, dated September 28, 1897.

Application filed June 30, 1897. Serial No. 643,036. Term of patent 14 years.

To all whom it may concern:

Be it known that I, ELIHU THOMSON, a citizen of the United States, residing at Swampscott, in the county of Essex, State of Massachusetts, have invented and produced a new and original Design for Wings for Air-Blasts, (Case No. 587,) of which the following is a specification, reference being had herein to the accompanying drawings, in which—

10 Figure 1 is a view in perspective of a wing for an air-blast constructed according to my design, and Fig. 2 is a cross-section.

As shown in the drawings, the leading or material feature of the design is a rectangular block having flat parallel sides, one of which is hollowed out.

Referring now by letter, the wing A is provided with flat parallel surfaces C and B.

The former I have designated as the "front" and the latter as the "back." The front is 20 hollowed out, as shown at D. The ends E and F are flat and form right angles with the front and back. The side G is curved slightly and in such manner that the front surface C is a trifle longer than the back surface B. Side 25 H extends parallel to side G and is rounded, so that it forms a semicircle.

Having thus described my invention, what I claim is—

The design for a wing for an air-blast, substantially as described and shown.

ELIHU THOMSON.
